GRINDING DEVICE

Joseph Hribar, Lockport, Ill.

Application July 20, 1936, Serial No. 91,611

14 Claims. (Cl. 51—241)

This invention relates particularly to a grinding device which may be usefully employed in grinding the connecting-rod bearings of a crank-shaft, for example.

5 The primary object is to provide a device of this character which may be used to grind the connecting-rod bearings without the necessity of removing the crank-shaft from the main bearings of the engine.

10 The invention is illustrated in a preferred embodiment in the accompanying drawings, in which—

Fig. 1 is an edge elevational view of a desirable embodiment of the invention; Fig. 2, a view at right angles to the view shown in Fig. 1, illustrating the grinding device in position for grinding a crank-bearing of a crank-shaft, the handle of the device being shown brokenly; Fig. 3, a longitudinal sectional view of the improved device; Fig. 4, an enlarged broken sectional view taken as indicated at line 4 of Fig. 3; and Fig. 5, an enlarged sectional view taken as indicated at line 5 of Fig. 3.

It may be stated preliminarily that the improved grinding device is adapted to be suspended from a crank of the crank-shaft after the crank has been disconnected from the connecting-rod joining it to the piston of the engine; also, that the grinding device preferably employs 25 a belt-like grinding element which preferably is operated by an electric motor, the grinding being effected while the engine-motor turns slowly. It will be understood that in operation the upper end of the implement follows the movements of 30 the crank-shaft while the operator of the grinding device steadies and guides the lower end of the implement by means of the handle with which it is equipped.

In the embodiment illustrated, A designates a 40 main frame which is adapted to be suspended from a crank-portion B of a crank-shaft; C, an inner frame which is longitudinally adjustable and which is equipped at its lower end with a rigidly secured threaded stem, or adjusting screw, C'; D, a belt-like grinding element carried by an upper roller D' and a lower roller D² journaled in the inner frame C; E, a handle fixedly secured to and depending from the lower end of the main frame A; and F, an internally threaded sleeve (or nut) connected with the threaded stem C' and having a head portion F' journaled in the lower end of the handle E, from which depends a reduced extension F² on which is rigidly secured a graduated actuating knob F³.

55 The nut F and the attendant parts serve as a

micrometer adjustment for the inner frame C, enabling the grinding element D to be nicely adjusted with relation to the bearing-portion B of the crank-shaft.

The main frame A of the device preferably is 5 constructed of a plurality of members which may be taken apart at will. In the illustration given, the frame comprises an angular base-portion 1 which affords an end-member 1^a and a longitudinal member 1^b, the tubular handle E 10 being fixedly mounted in the end-member 1^a; a side-member 2 having its lower portion secured by cap-screws 2^a to the member 1^b; and a side-member 3 having its lower end secured by cap-screws 3^a to the end-member 1^a. The upper end- 15 portions of the side-members 2 and 3 are curved towards each other, as indicated at 2^b and 3^b respectively. The ends of the members overlap and are interlocking connected, as by means of a hook and groove connection indicated at 4 20 and a pin and hole connection as indicated at 5.

When the screws 3^a are removed, the member 3 25 may be swung outwardly and upwardly and then lifted away from the upper end of the member 2, the interlock connections at 4 and 5 permitting this action.

The inner surface of the upper end-portion of the member 2 is equipped with a bearing-block 6 which is secured in position by screws 6^b. The inner surface of the side-member 2 is provided 30 with a guide 7 in which is adjustably mounted a bearing-member 7^a. The member 7^a is secured to the side member 2 by means of a head-screw 7^b which may be adjusted in a slot 8 with which the member 2 is provided.

Similarly, the side-member 3 is equipped at its inner side with a guide 9 in which is mounted a bearing-member 9^a secured by means of a screw 9^b which can be adjusted in a slot 10 with which the side member 3 is provided.

The bearing 7^a may be adjusted towards the crank-shaft by means of an adjusting screw 11 which has threaded connection with a lug 11^a carried by the side member 2.

The bearing member 9^a may be adjusted towards the crank-shaft by means of an adjusting rod 12 whose upper end has threaded connection with a lug 12^a carried by the side member 3. The lower end of the rod 12 extends through a bearing lug 12^b with which the side-member 3 50 of the main frame is provided at its lower end. The lower extremity of the adjusting rod 12 is equipped with a knurled head 12^c which is disposed a short distance below the end-member 1^a of the main frame.

The bearings 6, 7^a and 9^a with which the main frame is equipped afford a three-point bearing of the main frame against the crank-shaft.

The inner frame C is shown as comprising an angle-form base-member 13 which affords an end-member 13^a and a longitudinal member 13^b. The longitudinal member 13^b has sliding dovetailed connections with the longitudinally disposed member 1^b of the main frame; a complementary member 14 secured to the member 13 by a lower cap-screw 15 and upper cap-screws 16; a tubular member 17 surmounting the member 14 and equipped with flanges 17^a, said flanges being secured to the member 14 by the cap-screws 16 which serve also to connect the member 14 with the base-member 13 of the inner frame; a tubular plunger, or guide member 18, extending within the tubular member 17, the member 18 being equipped at its upper end with a flange 18^a which is secured to a head, or block, 19 in which the upper roller D' is journaled, the parts being connected by small bolts 20, as shown in Fig. 3; a spring 21, confined between the lower end of the tubular plunger 18 and the member 14; and a clamping screw 22 by means of which the members 17 and 18 may be rigidly connected together at will.

The spring 21 may serve to give desired tension to the belt-like grinding element D, after which the clamping screw 22 may be tightened if desired. It may be stated that the upper portion of the tubular member 17 is provided with a longitudinal slot, as indicated at 17^a, the clamping screw 22 extending across this slot.

The tubular member 17 may be provided with a transverse perforation, indicated at 23; and the tubular member 18 may be provided at a somewhat higher point with a perforation 24. When desired, the set screw 22 may be loosened, the plunger 18 may be depressed to slacken the belt, and a pin (not shown) may be inserted through the perforation 24 into the perforation 23, when these perforations are in registration. This may be done when it is desired to remove the belt D. To permit such removal, the lower portion of the inner frame may be provided with a slot 25 (Figs. 1 and 3) in which is removably secured a fillet 25^a which is held in place by the cap-screws 15.

The lower roller D² is journaled in the lower portion of the inner frame C. It is provided with a shaft 26 journaled in bearings 27 with which the inner frame is provided. These bearings may be ball-bearings if desired. The shaft 26 extends transversely of the frame; and, as will be understood from Figs. 1 and 5, the shaft is connected with a flexible shaft 28 which may be driven by means of an electric motor (not shown). In practice, the electric motor may be direct-coupled to the shaft 26, so that the roller D² which drives the belt D may be actuated at high speed. A speed of two or three thousand revolutions a minute is suitable.

The lower roller D² preferably is crowned very slightly at 29. The upper roller D' should be a true cylinder, however. It may be provided with transverse grooves 30 which permit some air circulation and tend to have a cooling effect.

From the description given, the operation will be readily understood. When the crank of a crank-shaft requires grinding, the connecting rods from the pistons may be removed, after first dropping off the bottom of the crank-case.

After removing the side member 3 of the main frame of the grinding implement, the implement

may be hooked over a crank of the crank-shaft. The bearings 7^a and 9^a with which the main frame of the implement is equipped may be suitably adjusted with relation to the bearing member 6 to properly center the upper portion of the main frame upon the crank, it being understood that the frame-member 3 is re-applied after the implement has been hung upon the crank. By means of the micrometer adjustment indicated at F—F³, the grinding element D may be adjusted to make suitable contact with the crank of the crank-shaft B. The engine may be turned at a slow speed. The grinding element may be operated at high speed by means of an electric motor, or other source of power. It would be possible, of course, to gear the grinding element of the improved implement to the engine of the automobile, if desired.

The range of adjustability of the bearing members 7^a and 9^a is sufficient to enable the implement to be adjusted to the usual range of shafts employed in connection with automobile engines.

The outer surface of the member 1^b of the main frame preferably is bowed slightly. That is, the outer surface is slightly convex in a longitudinal direction, as indicated at 31 in Fig. 3. One of the screws 2^a is located above the point where the member 2 bears against the convex surface, and the other screw 2^a is located below that point. Accordingly, the screws may be used as a means for truing up or giving proper symmetry to the frame, depending upon the extent to which the screws are turned inwardly, respectively.

The upper roller D is shown provided with a roller bearing. This is desirable because of the high speed at which the grinding element is operated. The endless belt 1 which forms the grinding element D may have its outer surface coated with fine carborundum or the like. It is possible, of course, to use grinding-belts having different abrasive effects. For example, a belt of rather high abrasive effect may be employed in the first portion of the grinding operation, and then a belt with an extremely fine grinding surface may be employed for finishing purposes.

The improved implement enables the ordinary work of grinding the connecting-rod bearings of an automobile engine crank-shaft to be effected expeditiously and at relatively small expense. The bearings may be toned up accurately by means of the improved implement without removing the crank-shaft.

The frame-member 2 is a strong, substantial frame-member and is secured very strongly to the base-member 1 of the frame. By reason of the convex surface indicated at 31 and the connecting-screws 2^a, the desired degree of verticality of the member 2 may be firmly established. The opposite side member 3 is shown of thinner metal and its position is regulated by the member 2. In this manner, the desired symmetry of the frame is attained; and the inner frame C, by reason of the substantial sliding connection which it has with the member 1^b, assures a true contact between the grinding belt and the crank-shaft. It has been found that by very slightly crowning the roller D, the belt will stay on the rollers without difficulty. The upper roller should present a true generally cylindrical surface, in order that the grinding belt may have line contact with the shaft which is being ground.

The foregoing detailed description has been given for clearness of understanding only, and

no unnecessary limitations should be understood therefrom, but the appended claims should be construed as broadly as permissible in view of the prior art.

5. What I regard as new and desire to secure by Letters Patent is:

1. A grinding implement of the character set forth, comprising an elongated frame equipped at its upper end with a crank-shaft bearing; a flexible endless belt of abrasive material mounted on a roller journaled in said frame; means for driving said belt; and means for adjusting said belt towards and away from the crank-shaft.

2. A grinding implement as specified in claim 1, in which said belt is mounted upon a pair of rollers journaled in a longitudinally adjustable inner frame mounted in the main frame.

3. A grinding implement as specified in claim 1, in which said belt is mounted upon a pair of rollers journaled in a longitudinally adjustable inner frame mounted in the main frame, said inner frame being equipped with a rigidly secured threaded stem and said outer frame being equipped with a micrometer adjustment acting through the medium of said threaded stem.

4. A grinding implement of the character set forth, comprising a main frame equipped internally at its upper portion with a bearing adapted to engage the upper surface of a crank and having its sides equipped with adjustable bearings adapted to engage the lower portion of the crank; an endless belt grinding element, of substantially the same width as said frame, adjustably mounted on rollers journaled in said frame; and means for driving said grinding element.

5. A grinding implement as specified in claim 4, having the lower end of the main frame equipped with a depending handle.

6. A grinding implement as specified in claim 4, in which the lower end of the main frame is equipped with a depending tubular handle and in which the grinding element is carried by an inner frame having an adjusting stem housed in said handle.

45. 7. A grinding implement of the character set forth, comprising: a main frame comprising detachably related side-members having an interlock connection at their upper ends; a lower frame-member interposed between and secured to the lower portion of said side-members; an inner frame adjustable longitudinally within said main frame; an endless-belt grinding-element carried by rollers journaled in said inner frame; and means for actuating the lower roller and thereby actuating the grinding-element.

8. A grinding implement of the character set forth, comprising: an outer frame comprising detachably related elongated frame-members; bearings mounted in the upper portion of said frame and adapted to engage a crank from which the main frame may be suspended; an inner frame adjustable longitudinally of the

main frame; rollers mounted in the upper and lower end-portions of the inner frame; a grinding-belt mounted on said rollers; and means for actuating the lower roller.

9. A grinding implement as specified in claim 8, in which the main frame is equipped with an adjusting rod for one of the bearings which engages the crank, said adjusting rod extending through the lower end of the main frame.

10. A grinding implement as specified in claim 8, having the lower end of the main frame equipped with a tubular handle and having the inner frame equipped with an adjusting stem extending axially into said handle; and a nut mounted in the lower portion of said handle and engaging said adjusting stem, said nut having actuating means disposed below the lower end of said handle.

11. A grinding implement comprising an outer frame composed of detachably connected elongated members; bearings for a crank-shaft in the upper portion of said frame; an inner adjustable frame disposed below the space for the crank-shaft; an endless-belt grinding element mounted in said inner frame; and means for actuating said grinding element.

12. A grinding element comprising a main frame consisting of detachably related members; bearings in the upper portion of said frame adapted to engage a crank; a handle connected with the lower end of said frame; an inner frame comprising collapsibly related upper and lower members; rollers journaled in said upper and lower members; a grinding belt mounted on said rollers; means for actuating the lower roller; and means for adjusting the inner frame longitudinally of the main frame.

13. In an implement of the character set forth: a main frame of elongated form comprising detachably connected members, said frame being equipped internally at its upper end with bearings for engaging a crank-shaft; an inner frame provided with rollers adjustably connected with the outer frame; an endless grinding belt mounted on said rollers and adapted to engage the crank-shaft when properly adjusted; and means for actuating said grinding element relative to the main frame.

14. In an implement of the character set forth: a main frame of elongated form comprising detachably connected members, said frame being equipped internally at its upper end with bearings for engaging a crank-shaft; a longitudinally collapsible inner frame adjustably connected with the outer frame and provided with supporting rollers; an endless grinding belt mounted on said rollers and adapted to engage the crank-shaft when properly adjusted; and means for actuating said grinding element relative to said main frame.

JOSEPH HRIBAR.
